AXIAL-TYPE HYDRODYNAMIC MACHINE

Adolf Grad, Wauwatosa, Wis., assignor to The Oilgear Company, Milwaukee, Wis., a corporation of Wisconsin

Application May 5, 1947, Serial No. 746,018

26 Claims. (Cl. 103—162)

1

This invention relates to rotary hydrodynamic machines which will function as pumps when driven mechanically and will function as motors when supplied with liquid under pressure. The machine to which the invention relates in particular is of the type having a cylinder barrel which rotates on a stationary axis, a plurality of pistons and cylinders arranged in the cylinder barrel around and parallel to its axis of rotation, and a thrust member which effects reciprocation of the pistons during rotation of the cylinder barrel.

The principal object of the invention is to provide a hydrodynamic machine which will have a higher overall efficiency when operating at high pressures than prior machines of the same general type.

Another object is to provide an axial type hydrodynamic machine which when functioning as a pump is capable of delivering a large volume of liquid at a very high pressure.

Another object is to improve the construction of axial type hydrodynamic machines.

Other objects and advantages will be apparent from the description hereinafter given of a hydrodynamic machine in which the invention is embodied.

Since the functions of a pump and the functions of a motor are substantially opposite to each other, a machine embodying the invention will be referred to herein as a pump but the invention is equally applicable to a motor and it is to be understood that the term "pump" as used herein means a hydrodynamic machine regardless of whether the machine functions as a pump or as a motor.

The invention is exemplified by the pump shown in the accompanying drawings in which the views are as follows:

Fig. 1 is a longitudinal horizontal section taken through the center of the pump and showing the parts in the positions occupied when pump displacement is substantially zero, the plane of the view being indicated by the line 1—1 of Fig. 3.

Fig. 2 is a longitudinal vertical section through the pump showing the parts in the positions occupied when pump displacement is substantially maximum, the plane of the view being indicated by the irregular line 2—2 of Fig. 3.

Fig. 3 is an end view of the pump with a part of the gear pump housing shown in section in order to expose certain channels, the view being taken on the line 3—3 of Fig. 2 and drawn to a scale larger than that of Figs. 1 and 2.

Fig. 4 is a face view of the valve which controls

2

the flow of liquid to and from the pump cylinders, the plane of the view being indicated by the line 4—4 of Fig. 2.

Fig. 5 is a section through the valve and portions of the adjacent parts, the plane of the view being indicated by the line 5—5 of Fig. 4.

Fig. 6 is a vertical section taken on the line 6—6 of Fig. 2.

Fig. 7 is a vertical transverse section taken on the line 7—7 of Fig. 2 and showing the arrangement of the pistons and cylinders in the cylinder barrel.

Fig. 8 is a transverse vertical section taken on the irregular line 8—8 of Fig. 1 and showing means for adjusting pump displacement and certain details of a valve like element which functions as a thrust bearing.

Fig. 9 is a face view of the valve like element shown in Figs. 1, 2 and 8, the view being taken in the plane indicated by the line 9—9 of Fig. 2 and drawn to a larger scale.

Fig. 10 is a section through the valve like element and portions of adjacent parts, the view being drawn to the same scale as Fig. 9 and taken in the plane indicated by the line 10—10 of that figure.

Fig. 11 is a circuit diagram illustrating the manner in which liquid is supplied to the hold-up motors shown in Figs. 8—10, the upper part of the diagram being a partial section taken on the line A—A of Fig. 9 and drawn to a larger scale.

Fig. 12 is a diagram of a hydraulic circuit which effects retraction of the pump pistons.

The pump chosen for illustration has its mechanism arranged within and supported by a housing or case 1 which has a removable end head 2 at its rear end and is provided with suitable supporting brackets not shown.

Case 1 encloses a rotatable cylinder barrel 3 which is fixed to a drive shaft 4 and is rotatably supported at its rear end by a bearing 5 carried by end head 2. Shaft 4 is supported near its front end by a bearing 6 carried by the front wall of case 1 so that cylinder barrel 3 is supported for rotation upon an axis which is horizontal in respect to Fig. 2.

Cylinder barrel 3 has a plurality of cylinders 7—8 and pistons 9—10 arranged therein around and parallel to its axis of rotation. Each cylinder includes an outer or forward portion 7 which extends inward from the front end of cylinder barrel 3, and a coaxial inner or rear portion 8 which is smaller than portion 7 and extends rearward therefrom. Each piston in-

cludes a non-pumping portion 9, which is of substantially the same diameter as the cylinder portion 7 and is closely fitted for reciprocation therein, and a coaxial pumping portion 10 which is of substantially the same diameter as cylinder portion 8 and is closely fitted for reciprocation therein. Portions 9 and 10 are fixed to or formed integral with each other and provide a shoulder 11 at the junction of the two portions.

Each piston 9-10 is forced inward mechanically and the pumping portion 10 thereof ejects liquid from the inner portion 8 of its cylinder during one-half of each revolution of cylinder barrel 3 and each piston 9-10 is retracted or moved outward and draws liquid into the portion 8 of its cylinder during the other half of each revolution of cylinder barrel 3 as will presently be explained.

Retraction of pistons 9-10 may be accomplished in any suitable manner but preferably they are retracted by fluid pressure such as by liquid which is supplied at a low pressure to the rear ends of cylinder portions 7 and acts upon shoulders 11. Liquid under pressure may be supplied to the rear ends of cylinder portions 7 in any suitable manner from any suitable source.

As shown, shaft 4 has the rear portion thereof reduced in diameter and extended through end head 2 to drive a gear pump from which liquid is supplied to cylinder portions 7 through a passage 15 which extends axially through the reduced rear portion of shaft 4, a passage 16 which extends radially from passage 15 and opens into an annular groove 17 formed in the peripheral surface of shaft 4, and a plurality of passages 18 one of which extends from each cylinder portion 7 through the wall of cylinder barrel 3 into communication with groove 17.

The gear pump (Figs. 1-3) has its driven gear 19 fixed upon the rear end portion of shaft 4 and its idler gear 20 rotatably supported by a stub shaft 21 which is carried by a gear pump housing 22 fixed to the rear end of end head 2. Gears 19 and 20 are arranged within a suitable recess 23 which is formed in housing 22 and is divided by gears 19 and 20 into an intake chamber 24 and a discharge chamber 25. Recess 23 has its open side closed by a plate 26 which is clamped between housing 22 and the rear face of end head 2.

Intake chamber 24 is connected by a channel 27 to a source of liquid supply such as a reservoir 28 as shown schematically in Fig. 12. Discharge chamber 25 opens into a passage 29 which is formed in housing 22 and communicates with an annular groove 30 formed in the rear end portion of shaft 4. Opposite sides of groove 30 are connected by a passage 31 which extends through shaft 4 and communicates with passage 15 so that liquid from gear pump 19-20 may flow from discharge chamber 25 through passage 29, groove 30, passages 31, 15 and 16, groove 17 and passages 18 to the inner ends of cylinder portions 7.

For the purpose of illustration, the pump has been shown provided with manually operated means for varying its displacement as will presently be explained but in practice it preferably is provided with hydraulically operated displacement varying means. In order that the liquid discharged by gear pump 19-20 may be employed for operating the displacement varying means and/or for other purposes, passage 29 has been shown as having connected thereto a channel 32 through which liquid may be directed from gear pump 19-20 to a remote point or points. The

liquid discharged by gear pump 19-20 in excess of requirements is exhausted through a relief valve 33 (Fig. 12) which discharges through a channel 34 into reservoir 28 and which enables gear pump 19-20 to maintain a predetermined low pressure in the several passages and channels and in the cylinder portions 7.

Each piston 9-10 is moved inward during one-half of each revolution of cylinder barrel 3 by means to be presently described and each piston is moved outward during the other half of each revolution of cylinder barrel 3 by the pressure in cylinder portion 7 acting upon shoulder 11. The inward moving pistons eject liquid from the cylinder portions 7 in which they are fitted and this liquid flows through passages 18 and groove 17 to the cylinder portions 7 containing the outward moving pistons. Since the sum of the displacements of the inward moving pistons is the same as the sum of the displacements of the outward moving pistons, gear pump 19-20 need supply to cylinder portions 7 only sufficient liquid to make up for leakage losses.

The inward moving pistons eject liquid from the portions 8 of the cylinders in which they are fitted and the outward moving pistons draw liquid into the portions 8 of the cylinders in which they are fitted. Liquid flows to and from each cylinder portion 8 through a passage 40 extending therefrom inward and rearward through the rear face of cylinder barrel 3 which is made flat and smooth and constitutes a valve seat 41 for a floating flat valve 42 which controls the flow of liquid to and from cylinder portions 8. Valve seat 41 has been shown as being formed upon a hardened insert 3a which has portions of passages 40 formed therein and which is rigidly secured in cylinder barrel 3 to form substantially an integral part thereof but cylinder barrel 3 may be made of a single piece of material if desired.

Valve seat 41 engages an annular valve face 43 (Figs. 4 and 5) which protrudes slightly from the front end of valve 42 and is made flat and smooth. Valve 42 is supported by two pins 44 (Figs. 1 and 4) which are inserted into it and into end head 2. Pins 44 prevent valve 42 from rotating but they have sufficient clearance to permit valve 42 to be so adjusted that its face 43 bears evenly upon valve seat 41.

During rotation of cylinder barrel 3, each passage 40 registers alternately with two crescent shaped valve ports 45 and 46 which extend into valve 42 from its face 43, the adjacent ends of ports 45 and 46 being spaced apart a distance equal to or slightly greater than the width of a passage 40 in order to provide a seal between the two ports.

Ports 45 and 46 are connected through a plurality of hold-up motors to two passages 47 and 48 which are formed in end head 2 and are adapted to be connected to opposite sides of an external circuit as by means of two channels 49 and 50. As shown, two holes 51 extend rearward from the bottom of port 45 into communication with two hold-up motors 52 which are arranged within valve 42 and communicate with passage 47 through two passages 53 formed in end head 2, and two holes 54 extend rearward from the bottom of port 46 into communication with two hold-up motors 55 which are arranged within valve 42 and communicate with passage 48 through two passages 56 formed in end head 2.

All four of the hold-up motors 52 and 55 are identical and each includes a cylinder 57 which is formed in valve 42 concentric with a hole 51

or 54, a hollow piston 58 which is closely fitted in cylinder 57 to slide therein, an annular sealing member 59 which is arranged between piston 58 and the rear face of end head 2, and a spring 60 which is arranged within cylinder 57. Cylinder 57, hollow piston 58 and annular sealing member 59 thus form a channel for the free flow of liquid between a hole 51 or 54 and a passage 53 or 56.

The abutting surfaces of sealing member 59 and end head 2 are made flat and smooth and the abutting surfaces of sealing member 59 and piston 58 are made spherical and smooth to form substantially liquid tight joints between valve 42 and end head 2 and to permit valve 42 to so adjust itself that all of the sealing members bear evenly upon the rear face of end head 2 and the face 43 of valve 42 bears uniformly upon valve seat 41. Spring 60 urges piston 58 against sealing member 59 and sealing member 59 against end head 2, and the springs 60 of all of the hold-up motors urge valve 42 against valve seat 41 to thereby maintain substantially liquid tight seals between valve seat 41 and valve 42 and between valve 42 and end head 2.

The arrangement is such that when the pump is adjusted to deliver liquid in one direction and cylinder barrel 3 is rotated, the gear pump liquid acting upon the shoulders 11 will move each piston 9-10 outward during one-half of each revolution of cylinder barrel 3 and each piston 9-10 will be forced inward during the other half of each revolution of cylinder barrel 3 by means to be presently described. The portions 10 of the outward moving pistons will draw liquid into the portions 8 of their cylinders through the passages 40 connected thereto, valve port 45, holes 51, hold-up motors 52, passages 53 and passage 47 from channel 49. Portions 10 of the inward moving pistons will eject liquid from the portions 8 of their cylinders through the passages 40 connected thereto, valve port 46, holes 54, hold-up motors 55, passages 56 and passage 48 into channel 50. When the pump is adjusted to deliver liquid in the opposite direction, the flow through the above channels will be reversed.

When the pump is delivering liquid under pressure, there is a minute flow of liquid from the high pressure valve port across valve face 43 to form a lubricating film between it and valve seat 41 and pump pressure extends into this film. The pressure created by the pump causes the liquid in the passages 40 on the high pressure side of the pump, the liquid in the high pressure port and the liquid in the film adjacent the high pressure port to exert a blow-off force which tends to move valve 42 away from valve seat 41. However, the same pressure acts upon the ends of the cylinders 57 and the pistons 58 of the hold-up motors on the high pressure side of the pump and thereby enables those motors to urge valve 42 against valve seat 41 with a force proportional to pump pressure. The blow-off force also tends to move cylinder barrel 3 away from valve 42 but is prevented from doing so by bearings 5 and 6, by the pressure created by pistons 9-10 acting upon the rear ends of cylinder portions 8 and by gear pump pressure acting upon the rear ends of cylinder portions 7. The parts are so proportioned that the sum of the forces exerted by the liquid upon the rear ends of cylinder portions 7 and 8 is nearly as great as the blow-off force so that only a small axial load is imposed upon bearings 5 and 6.

The magnitude of the blow-off force at any given pressure is determined by the effective area

of the face of the valve. Also, power losses in a ball bearing vary directly in accordance with the size of the bearing. Therefore, in order to keep the blow-off force and the bearing losses at minimums, the effective area of valve 42 and the size of bearing 5 should be as small as possible. This is accomplished by extending passages 40 radially inward from their respective cylinders and then extending them axially outward as close to the rotor axis as is practicable so that the effective area of the face of valve 42 and the diameter of bearing 5 may be minimums.

Since a pump ordinarily has an odd number of cylinders, the number of passages 40 containing liquid under pressure will change from odd to even or from even to odd each time a passage 40 passes from one valve port to the other. If the hold-up motors were made large enough to hold valve 42 against its seat when the maximum number of passages contained liquid under pressure, the force exerted by the hold-up motors would be in excess of requirements when only a minimum number of passages contained liquid under pressure and this excess force would impose an unnecessary drag upon cylinder barrel 3 and probably would cause abrasion of valve seat 41 and/or valve face 43. If the hold-up motors were only large enough to hold the valve to its seat when the minimum number of passages contained liquid under pressure, the valve would lift off its seat when the maximum number of passages 40 contained liquid under pressure. Not only does the magnitude of the blow-off force vary, but also the center of the blow-off force shifts radially in response to each variation in the number of passages 40 containing liquid under pressure.

In order to compensate for variations in the magnitude of the blow-off force and for shifting of the center of the blow-off force, the pump is provided with balancing motors which are energized and de-energized and thereby vary the magnitude and center of the hold-up force in response to changes in the number of passages 40 containing liquid under pressure. As shown in Figs. 2 and 4, valve 42 has two cylinders 61 extending inward from the rear face thereof and located behind the spaces between adjacent ends of ports 45 and 46, a piston 62 fitted in each cylinder 61 and engaging the front face of end head 2, and a duct 63 extending from each cylinder 61 through valve face 43 into the path of passages 40. Each balancing motor is energized and exerts an additional hold-up force on valve 42 each time a passage 40 registers with a duct 63 leading from the cylinder 61 of that motor.

Pistons 9-10 have the outer ends or heads thereof made spherical and in contact with a flat reaction surface 64 formed upon an annular thrust member which extends around shaft 4 and will effect reciprocation of pistons 9-10 when its axis is inclined to the cylinder barrel axis and cylinder barrel 3 is rotated. The thrust member has been shown as having a tubular outer part 65 which has its rear end flanged and reaction surface 64 formed thereon, and an inner tubular part 66 which telescopes with part 65 and has its front end flanged and in engagement with a valve like hold-up element or hydraulic thrust bearing 67 presently to be described.

Thrust member 65-66 is rotatably supported within a hollow reaction member or cradle 68 having in the front wall thereof an opening 69 through which shaft 4 extends. Cradle 68 is piv-

oted near its rear end upon two trunnions 70 and 71 which are fixed in opposite side walls of case 1 in alignment with each other and restrain cradle 68 from axial movement while permitting it to be swung thereon through limited angular distances to vary the angle between surface 64 and the axis of cylinder barrel 3. The common axis of trunnions 70 and 71 passes through the plane of reaction surface 64 so that swinging cradle 68 upon the trunnions causes surface 64 to rotate 10 upon the trunnion axis.

Cradle 68 preferably is swung upward and downward upon trunnions 70 and 71 to vary pump displacement and to reverse the direction of pump delivery by hydraulic means including servomotors which are energized by liquid supplied thereto from gear pump 19-20 under the control of a suitable pilot valve but for the purpose of illustration the pump has been shown provided with manually operable means including a hand-wheel 72 (Fig. 8) which is threaded upon a rod 73 and is restrained from axial movement by a socket 74 carried by case 1. Rod 73 extends through case 1 and is connected by a ring 75 to a projection 76 carried by cradle 68 near the front end thereof. When wheel 72 is rotated in one direction or the other, rod 73 will swing cradle 68 upward or downward upon trunnions 70 and 71 and thereby vary the angle between reaction surface 64 and the axis of cylinder barrel 3.

Thrust member 65-66 has been shown as being rotatably supported within cradle 68 by two bearings 77 and 78 which have the inner races thereof fitted upon part 65 and the outer races thereof fitted in cradle 68. The inner race of bearing 77 engages the inner face of the flange on part 65, the outer race of bearing 78 engages a shoulder 79 formed on cradle 68, and a spacer ring 80 is fitted between the inner races of the two bearings so that the two bearings and spacer ring prevent thrust member 65-66 from being moved forward by the pumping forces.

When cylinder barrel 3 is rotated, thrust member 65-66 will be rotated by the frictional contact of pistons 9-10 with reaction surface 64. If surface 64 is normal to the cylinder barrel axis as shown in Fig. 1, pistons 9-10 will not be reciprocated in response to rotation of cylinder barrel 3 but, if cradle 68 is swung upon trunnions 70 and 71 to incline reaction surface 64 to the cylinder barrel axis as shown in Fig. 2, each piston will be moved progressively inward by thrust member 65-66 during one-half of each revolution of cylinder barrel 3 and it will be moved progressively outward during the other half of each revolution of cylinder barrel 3 by the pressure acting upon its shoulder 11.

The outer end or head of each piston 9-10 is made spherical so that reaction surface 64 will engage the head of each piston upon a single contact spot in all positions of thrust member 65-66. When reaction surface 64 is normal to the cylinder barrel axis the contact spot is on the axis of the piston but at that time rotation of cylinder barrel 3 does not cause reciprocation of the pistons and the outer end of each piston revolves about the cylinder barrel axis in a circular path so that there is no relative movement between it and surface 64.

When reaction surface 64 is inclined to the cylinder barrel axis, the contact spot is off-set from the piston axis, the piston is reciprocated during rotation of the cylinder barrel and its outer end or head revolves in a path which is

slightly elliptical so that there is a slight relative movement between the piston head and surface 64. The radius of the piston head preferably is such that the contact spot is adjacent the periphery of the piston when surface 64 has a maximum inclination to the axis of cylinder barrel 3. The portion 9 of each piston 9-10 preferably is of such a diameter that the contact spot may be offset far enough from the piston axis to cause the piston to rotate in its cylinder as it reciprocates therein to thereby eliminate sliding movement between the piston and reaction surface 64.

Since reaction surface 64 engages each piston upon a single spot, the pumping force transmitted to that piston is limited by the bearing value of that spot. The pumping force required to enable a piston to create pressure is equal to the product of the pressure and the cross-sectional piston area subjected to that pressure. If the piston were of uniform diameter and the radius of its head were such that the contact spot would be adjacent the periphery of the piston when the inclination of reaction surface 64 was maximum, the contact spot would not have sufficient bearing value to transmit the pumping force necessary to enable the piston to create a high pressure in its cylinder.

However, by increasing the radius of the piston head, the bearing value of the contact spot is multiplied by an amount approximately equal to the square of the amount by which the radius of the piston head is multiplied, but increasing the piston head radius necessitates increasing the diameter of the outer portion 9 of the piston in order that reaction surface 64 may engage the spherical piston head when the inclination of surface 64 is maximum.

Therefore, by making piston portion 9 larger than piston portion 8 and providing it with a spherical head having such a radius that the contact spot is adjacent the periphery of the piston when the inclination of surface 64 is maximum, a very high pressure can be created and the radial components of the pumping forces are landed upon a bearing surface of substantial area.

If the pistons were connected to the thrust member through universal joints so that the pistons would be retracted by the thrust member and universal joints were arranged within the cylinders according to common practice, the pump could not create high pressures for the reason that a universal joint small enough to be contained within a cylinder would not be capable of transmitting a pumping force large enough to create a high pressure in that cylinder. If the universal joints were made large enough to transmit large pumping forces and were arranged outside the cylinders, they would occupy so much space that fewer pistons and cylinders could be arranged in the cylinder barrel and the volumetric capacity of the pump would be correspondingly reduced. But by making the outer portion 9 of each piston larger in diameter than the pumping portion 8 and providing it with a spherical head which makes a spot contact with the reaction surface, the pump is capable of delivering a large volume of liquid at a high pressure.

The pumping force, which moves a piston inward when the pump is creating pressure, is transmitted through the contact spot on that piston and is normal to reaction surface 64. The pumping force is opposed by the pressure in the cylinder of that piston which causes it to be resolved into an axial component, which moves the piston inward, and a radial component which

extends to tilt the piston in its cylinder but cylinder portion 7 and piston portion 9 are so long that the radial component lands upon the wall of the cylinder at a point which is spaced a substantial distance from the outer end thereof even when the pump is at full stroke as will be obvious from an inspection of Fig. 12. Consequently, the outer end of the cylinder will not be worn into an oblong shape by the thrust of the piston and the radial load on bearings 71 and 78 will be very slight.

In order to avoid the excessive bearing losses which would result if all of the pumping forces were transmitted through bearings 71 and 78, the valve like hold-up element 67 is arranged between thrust member 65—66 and the front wall of cradle 68 to relieve bearings 71 and 78 from the greater part of the pumping forces. Element 67 is provided with a central opening 81 through which shaft 4 passes and it is held in position and prevented from rotating by two pins 82 which are inserted into it and into the front wall of cradle 68 and have sufficient clearance to permit the rear face of element 67 to bear uniformly upon the front face of thrust member 65—66.

Element 67 (Figs. 1 and 9) is similar to valve 42 (Figs. 1 and 4) in that it has an arcuate groove or port and a plurality of hold-up motors on each side of its vertical centerline. The hold-up motors in each side of element 67 are connected to the channel leading from the hold-up motors in the same side of valve 42 so that in either direction of pump delivery element 67 can exert a hold-up force in opposition to the pumping forces.

As best shown in Figs. 9 and 10, element 67 has formed in the rear face thereof two elongated arcuate pressure grooves 83 and 84 in only one of which pump pressure prevails at any given time, and two short drain grooves 85 each of which is arranged between adjacent ends of grooves 83 and 84. A duct 86 extends from each groove 85 through the inner wall of element 67 so that liquid collected in groove 85 may escape therefrom.

The hold-up motors in element 67 may vary in number and size according to requirements, any one of the hold-up motors on each side of the vertical centerline may be connected to the channel leading from the hold-up motors in the same side of valve 42 and the other hold-up motors in element 67 may have plain pistons and be supplied with liquid from ports 83 and 84.

As shown, element 67 has a hold-up motor 87 arranged upon one side of its vertical centerline and connected to groove 83 by a duct 88, two hold-up motors 89 arranged at each side of motor 87 and connected to groove 83 by ducts 90, a hold-up motor 91 arranged upon the other side of its vertical centerline and connected to groove 84 by a duct 92, and two hold-up motors 93 arranged at each side of motor 91 and connected to groove 84 by ducts 94.

All eight of motors 89 and 93 are alike and, as shown in Fig. 10, each includes a cylinder 95 which extends inward from the front face of element 67, and a solid piston 98 which is fitted in cylinder 95 and engages the end wall of cradle 68.

The two motors 87 and 91 are alike and, as shown in Fig. 11, each includes a cylinder 97 which extends inward from the front face of element 67, a tubular piston 98 which is fitted in cylinder 97, an annular sealing member 99 which is arranged between piston 98 and the end wall

of cradle 68, and a spring 100 which urges piston 98 against sealing member 99 and sealing member 99 against the end wall of cradle 68.

The abutting surfaces on each sealing member 99 and on cradle 68 are made flat and smooth to provide a liquid tight joint therebetween, and the abutting surfaces on each member 99 and on each piston 98 are made spherical and smooth to provide a liquid tight joint therebetween and to permit the rear face of element 67 to bear uniformly upon the front face of thrust member 65—66.

Hold-up motor 87 communicates through its piston 98 and its sealing member 99 with a passage 101 (Figs. 1 and 11) which extends through the wall of cradle 68 and communicates through a sealing member 102 with a passage 103 formed in trunnion 71. Passage 103 is connected to the channel leading from the port 46 in valve 42 such as being connected by a channel 104 to channel 50. Hold-up motor 91 communicates through its piston 98 and its sealing member 99 with a passage 105 which extends through the wall of cradle 68 and communicates through a sealing member 106 with a passage 107 formed in trunnion 70. Passage 107 is connected to the channel leading from the port 45 in valve 42 such as by being connected by a channel 108 to channel 49. The inner end of each of sealing members 102 and 106 is spherical and fitted in a complementary spherical seat formed in cradle 68 upon the trunnion axis to provide liquid tight joints between the trunnion and the cradle while permitting the cradle to swing upon the trunnions. Sealing members 102 and 106 are held to their seats by pressure acting upon the outer ends thereof.

The arrangement is such that, when shaft 4 rotates cylinder barrel 3 clockwise in respect to Fig. 7, and cradle 68 is swung upward as shown in Fig. 12, gear pump pressure acting upon shoulders 11 will move each piston progressively outward as it passes downward through the intake side of the pump, which is the right side in respect to Fig. 7, and thrust member 65—66 will force each piston progressively inward as it passes upward through the discharge side of the pump which is the left side in respect to Fig. 7. The portions 10 of the outward moving pistons will draw liquid into the portions 8 of their cylinders through the passages 40 connected thereto, the port 45 in valve 42, hold-up motors 52 and passages 53 and 47 from channel 49. The portions 10 of the inward moving pistons will eject liquid from the portions 8 of their cylinders through the passages 40 connected thereto, the port 46 in valve 42, hold-up motors 55 and passages 56 and 48 into channel 50.

When the pump creates pressure, pumping forces are transmitted through thrust member 65—66 to the pistons 9—10 on the discharge side of the pump and these pumping forces tend to move thrust member 65—66 forward. However, the pressure created by the pump extends through channels 50 and 104, passages 103 and 101, hold-up motor 87, duct 88 and groove 83 into all four hold-up motors 89, thereby energizing all of the hold-up motors on the discharge side of the pump and enabling them to exert upon thrust member 65—66 hold-up forces which are proportional to the pumping forces and act in opposition thereto. By providing hold-up motors in such numbers and of such size or sizes that the total hold-up force exerted thereby is only slightly less than the total pumping force,

11

bearings 77 and 78 are relieved of nearly all axial loads so that the bearing losses are very low.

Liquid escapes at a minute rate from groove 83 and forms between the abutting faces of element 67 and thrust member 65—66 a lubricating film which prevents metal-to-metal contact. The area of this film is limited for the reason that the contact face of element 67 extends only a very short distance inward and a very short distance outward from the edges of the grooves and the distance between each end of grooves 83 and 84 and the adjacent end of a drain groove 85 is very short.

The hold-up force is transmitted to thrust member 65 and 66 through the liquid in groove 83 and the lubricating film. The liquid in groove 83 constitutes a liquid bearing which is far more efficient than a mechanical bearing as it has been found in practice that only a very small torque is required to effect relative rotation of two parts which are urged together by a very large force and have a liquid bearing of this type therebetween.

When cradle 68 is swung downward below its neutral position, the pump will function in the above described manner except that it will discharge liquid into channel 49, the opposite side of the pump will be the discharge side, and pressure will extend from channel 49 to hold-up motors 91 and 93 and cause them to exert hold-up forces upon thrust member 65—66 in opposition to the pumping forces exerted thereon.

By providing a hold-up element or hydraulic thrust bearing to take the greater part of the piston thrust, bearings 77 and 78 may be much smaller than would be necessary if they had to take the entire piston thrust and, consequently, the bearing losses are reduced to a minimum.

The area to which the hold-up force is applied should not extend radially outward beyond the inner races of bearings 77 and 78. Consequently, the radius of grooves 83 and 84 is considerably smaller than the radius of the circle upon which pistons 9—10 are arranged. Keeping the radius of grooves 83 and 84 small is advantageous for the reason that, while the liquid in grooves 83 and 84 constitutes a substantially frictionless bearing, rotation of thrust member 65—66 causes the lubricating film of liquid between the thrust member and the faces of the lands surrounding grooves 83 and 84 to be sheared which causes some drag upon the thrust member and, by keeping the radius of grooves 83 and 84 small and thereby keeping the area of the lubricating film small, the drag is reduced to a minimum.

Pumping forces are transmitted from thrust member 65—66 to pistons 9—10 through an angle of nearly 180° and, if each of grooves 83 and 84 extended through an angle of nearly 180° as does each of the ports 45 and 46 in valve 42, the center of the hold-up force exerted upon thrust member 65—66 by element 67 would be radially inward a substantial distance from the resultant of the pumping forces and a moment would be created which would tend to tilt the thrust member and thereby impose an additional load upon bearings 77 and 78.

However, the center of the hold-up force may be moved radially outward into alignment with the resultant of the pumping forces by reducing the angular lengths of grooves 83 and 84 in accordance with the difference between the radius of grooves 83 and 84 and the radius of the piston circle and by providing drain grooves 85 between the adjacent ends of grooves 83 and 84. For

12

example, each of grooves 83 and 84 extends through an angle of about 124° in the pump shown and the center of the hold-up force is approximately in alignment with the resultant of the pumping forces. In another pump, it was necessary to reduce each of the grooves 83 and 84 to about 90° and to correspondingly increase the length of each of drain grooves 85 in order to bring the center of the hold-up force into alignment with the resultant of the pumping forces.

For the purpose of illustration, the pump has been shown connected to a reservoir 115 through the casing 116 of an automatic suction valve 117. Casing 116 communicates at its center with a channel 118 having a check valve 119 arranged therein and a relief valve 120 connected thereto. Channels 49 and 50 are connected, respectively, by two channels 121 and 122 to casing 116 at two points upon opposite sides of channel 118 and channels 121 and 122 are connected, respectively, by channels 123 and 124 to the adjacent ends of casing 116. The arrangement is such that, when the pump is reversed, it will at first tend to discharge through valve casing 116 into reservoir 115 but relief valve 120 will resist discharge of liquid therethrough and thereby cause pressure to be created. This pressure will extend from discharge channel 49 or 50 through channels 121 and 123 or channels 122 and 124 and shift valve 117 to a position in which the intake side of the pump is connected to reservoir 115 and the discharge side of the pump is blocked therefrom. The pressure created by the pump is limited by one or the other of two high pressure relief valves 125 and 126 which are connected between channels 121 and 122.

The invention herein set forth is susceptible of various modifications without departing from the scope of the invention which is hereby claimed as follows:

1. In a hydrodynamic machine, the combination of a case, a shaft journaled in said case and extending through the front end thereof, a cylinder barrel fixed upon said shaft to rotate therewith and having a plurality of cylinders arranged therein around and parallel to said shaft and a passage leading from each cylinder through the rear end of said cylinder barrel, a valve arranged upon the rear end of said cylinder barrel and cooperating with said passages to control the flow of liquid to and from said cylinders, a piston fitted in each cylinder and extending forward beyond the front end of said cylinder barrel, a thrust member cooperating with said pistons and adapted to force each piston rearward and cause it to eject liquid from its cylinder during one half of each revolution of said cylinder barrel, a reaction member arranged forward of said cylinder barrel and restrained by said case from movement axially of said shaft, a mechanical bearing carried by said reaction member to rotatably support said thrust member and to transmit pumping forces from one to the other, and means for relieving said mechanical bearing from at least a part of said pumping forces including a hold-up element engaging the front end of said thrust member and having grooves in the rear face thereof, hold-up motors reacting against said reaction member and adapted when energized to urge said element against said thrust member, and means for supplying liquid from said cylinders to said hold-up motors and said grooves.

2. In a hydrodynamic machine, the combination of a case, a shaft journaled in said case and

extending through the front end thereof, a cylinder barrel fixed upon said shaft to rotate therewith and having a plurality of cylinders arranged therein around and parallel to said shaft and a passage leading from each cylinder through the rear end of said cylinder barrel, a valve arranged upon the rear end of said cylinder barrel and cooperating with said passages to control the flow of liquid to and from said cylinders, a piston fitted in each cylinder and extending forward beyond the front end of said cylinder barrel, a thrust member cooperating with said pistons and adapted to force each piston rearward and cause it to eject liquid from its cylinder during one half of each revolution of said cylinder barrel, a reaction member arranged forward of said cylinder barrel and restrained by said case from movement axially of said shaft, a mechanical bearing carried by said reaction member to rotatably support said thrust member and to transmit pumping forces from one to the other, and means for relieving said mechanical bearing from at least a part of said pumping forces including a hold-up element engaging the front end of said thrust member and having grooves in the rear face thereof, hold-up motors arranged within said element and reacting against said reaction member, and means for supplying liquid from said cylinders to said hold-up motors and said grooves to cause said element to exert hold-up forces upon said thrust member in opposition to said pumping forces and to provide a liquid bearing between said element and said thrust member.

3. In a hydrodynamic machine, the combination of a case, a cylinder barrel rotatably supported within said case and having a plurality of cylinders arranged therein around and parallel to its axis of rotation and a passage leading from each cylinder through the rear end of said cylinder barrel, a piston fitted in each cylinder and extending forward beyond the front end of said cylinder barrel, a valve arranged upon the rear end of said cylinder barrel and cooperating with said passages to control the flow of liquid to and from said cylinders, a reaction member arranged forward of said cylinder barrel and restrained by said case from movement axially of said cylinder barrel, a thrust member carried by said reaction member and having upon the rear end thereof a reaction surface which engages the outer ends of said pistons and is inclined to the cylinder barrel axis to force each piston rearward and cause it to eject liquid from its cylinder during one half of each revolution of said cylinder barrel, a mechanical bearing carried by said reaction member to rotatably support said thrust member and to transmit pumping forces from one to the other, and means for relieving said mechanical bearing from at least a part of said pumping forces including a hold-up element engaging the front end of said thrust member and having grooves in the rear face thereof, hold-up motors reacting against said reaction member and adapted when energized to urge said element against said thrust member, and means for supplying liquid from said cylinders to said hold-up motors and said grooves.

4. In a hydrodynamic machine, the combination of a case, a cylinder barrel rotatably supported within said case and having a plurality of cylinders arranged therein around and parallel to its axis of rotation and a passage leading from each cylinder through the rear end of said cylinder barrel, a piston fitted in each cylinder

and extending forward beyond the front end of said cylinder barrel, a valve arranged upon the rear end of said cylinder barrel and cooperating with said passages to control the flow of liquid to and from said cylinders, a reaction member arranged forward of said cylinder barrel and restrained by said case from movement axially of said cylinder barrel, a thrust member carried by said reaction member and having upon the rear end thereof a reaction surface which engages the outer ends of said pistons and is inclined to the cylinder barrel axis to force each piston rearward and cause it to eject liquid from its cylinder during one half of each revolution of said cylinder barrel, a mechanical bearing carried by said reaction member to rotatably support said thrust member and to transmit pumping forces from one to the other, and means for relieving said mechanical bearing from at least a part of said pumping forces including a hold-up element engaging the front end of said thrust member and having grooves in the rear face thereof, hold-up motors arranged within said element and reacting against said reaction member, and means for supplying liquid from said cylinders to said hold-up motors and said grooves to cause said element to exert hold-up forces upon said thrust member in opposition to said pumping forces and to provide a liquid bearing between said element and said thrust member.

5. In a hydrodynamic machine, the combination of a case, a cylinder barrel rotatably supported within said case and having a plurality of cylinders arranged therein around and parallel to its axis of rotation and a passage leading from each cylinder through the rear end of said cylinder barrel, a valve arranged upon the rear end of said cylinder barrel and cooperating with said passages to control the flow of liquid to and from said cylinders, each of said cylinders including an inner pumping portion and an outer guiding portion larger in diameter than said pumping portion, pistons fitted in said cylinders, each of said pistons including a pumping portion fitted in the pumping portion of its cylinder and a larger guiding portion fitted in the guiding portion of its cylinder, a reaction member arranged forward of said cylinder barrel and restrained by said case from movement axially of said cylinder barrel, a thrust member carried by said reaction member and having upon the rear end thereof a reaction surface which engages the outer ends of said pistons and is inclined to the cylinder barrel axis to force each piston rearward and cause it to eject liquid from its cylinder during one half of each revolution of said cylinder barrel, means for maintaining in the inner part of the guiding portion of each of said cylinders a liquid pressure which urges said pistons against said reaction surface and moves said pistons outward during the other half of each revolution of said cylinder barrel, a mechanical bearing carried by said reaction member to rotatably support said thrust member and to transmit pumping forces from one to the other, and means for relieving said mechanical bearing from at least a part of said pumping forces including a hold-up element engaging the front end of said thrust member and having grooves in the rear face thereof, hold-up motors reacting against said reaction member and adapted when energized to urge said element against said thrust member, and means for supplying liquid from said cylinders to said hold-up motors and said grooves.

15

6. In a hydrodynamic machine, the combination of a case, a cylinder barrel rotatably supported within said case and having a plurality of cylinders arranged therein around and parallel to its axis of rotation and a passage leading from each cylinder through the rear end of said cylinder barrel, a valve arranged upon the rear end of said cylinder barrel and cooperating with said passages to control the flow of liquid to and from said cylinders, each of said cylinders including an inner pumping portion and an outer guiding portion larger in diameter than said pumping portion, pistons fitted in said cylinders, each of said pistons including a pumping portion fitted in the pumping portion of its cylinder and a larger guiding portion fitted in the guiding portion of its cylinder, a reaction member arranged forward of said cylinder barrel and restrained by said case from movement axially of said cylinder barrel, a thrust member carried by said reaction member and having upon the rear end thereof a reaction surface which engages the outer ends of said pistons and is inclined to the cylinder barrel axis to force each piston rearward and cause it to eject liquid from its cylinder during one half of each revolution of said cylinder barrel, means for maintaining in the inner part of the guiding portion of each of said cylinders a liquid pressure which urges said pistons against said reaction surface and moves said pistons outward during the other half of each revolution of said cylinder barrel, a mechanical bearing carried by said reaction member to rotatably support said thrust member and to transmit pumping forces from one to the other, and means for relieving said mechanical bearing from at least a part of said pumping forces including a hold-up element engaging the front end of said thrust member and having grooves in the rear face thereof, hold-up motors arranged within said element and reacting against said reaction member, and means for supplying liquid from said cylinders to said hold-up motors and said grooves to cause said element to exert hold-up forces upon said thrust member in opposition to said pumping forces and to provide a liquid bearing between said element and said thrust member.

7. In a hydrodynamic machine, the combination of a case, a cylinder barrel rotatably supported within said case and having a plurality of cylinders arranged therein around and parallel to its axis of rotation and a passage leading from each cylinder through the rear end of said cylinder barrel, a piston fitted in each cylinder and extending forward beyond the end of said cylinder barrel, a valve cooperating with said passages to control the flow of liquid to and from said cylinders, two trunnions carried by said case upon opposite sides thereof in axial alinement with each other, a reaction member arranged forward of said cylinder barrel and pivoted upon said trunnions, a thrust member carried by said reaction member and cooperating with said pistons to force each piston rearward and cause it to eject liquid from its cylinder during one-half of each revolution of said cylinder barrel, a mechanical bearing carried by said reaction member to rotatably support said thrust member and to transmit pumping forces from one to the other, and means for relieving said mechanical bearing from at least a part of said pumping forces including a hydraulic hold-up element carried by said reaction member in engagement with said thrust mem-

16

ber and energized by liquid supplied thereto from said cylinders to cause said element to exert hold-up forces upon said thrust member in opposition to said pumping forces and to provide a liquid bearing between said element and said thrust member.

8. In a hydrodynamic machine, the combination of a case, a cylinder barrel rotatably supported within said case and having a plurality of cylinders arranged therein around and parallel to its axis of rotation and a passage leading from each cylinder through the rear end of said cylinder barrel, a piston fitted in each cylinder and extending forward beyond the end of said cylinder barrel, a valve cooperating with said passages to control the flow of liquid to and from said cylinders, two trunnions carried by said case upon opposite sides thereof in axial alinement with each other, a reaction member arranged forward of said cylinder barrel and pivoted upon said trunnions, a thrust member carried by said reaction member and cooperating with said pistons to force each piston rearward and cause it to eject liquid from its cylinder during one half of each revolution of said cylinder barrel, a mechanical bearing carried by said reaction member to rotatably support said thrust member and to transmit pumping forces from one to the other, and means for relieving said mechanical bearing from at least a part of said pumping forces including a hold-up element engaging the front end of said thrust member and having grooves in the rear face thereof, hold-up motors reacting against said reaction member and adapted when energized to urge said element against said thrust member, and means for supplying liquid from said cylinders to said hold-up motors and said grooves.

9. In a hydrodynamic machine, the combination of a case, a cylinder barrel rotatably supported within said case and having a plurality of cylinders arranged therein around and parallel to its axis of rotation and a passage leading from each cylinder through the rear end of said cylinder barrel, a piston fitted in each cylinder and extending forward beyond the end of said cylinder barrel, a valve cooperating with said passages to control the flow of liquid to and from said cylinders, two trunnions carried by said case upon opposite sides thereof in axial alinement with each other, a reaction member arranged forward of said cylinder barrel and pivoted upon said trunnions, a thrust member carried by said reaction member and cooperating with said pistons to force each piston rearward and cause it to eject liquid from its cylinder during one half of each revolution of said cylinder barrel, a mechanical bearing carried by said reaction member to rotatably support said thrust member and to transmit pumping forces from one to the other, and means for relieving said mechanical bearing from at least a part of said pumping forces including a hold-up element engaging the front end of said thrust member and having grooves in the rear face thereof, hold-up motors arranged within said element and reacting against said reaction member, and means for supplying liquid from said cylinders to said hold-up motors and said grooves to cause said element to exert hold-up forces upon said thrust member in opposition to said pumping forces and to provide a liquid bearing between said element and said thrust member.

10. In a hydrodynamic machine, the combination of a case, a cylinder barrel rotatably sup-

ported within said case and having a plurality of cylinders arranged therein around and parallel to its axis of rotation and a passage leading from each cylinder through the rear end of said cylinder barrel, a valve cooperating with said passages to control the flow of liquid to and from said cylinders, each of said cylinders including an inner pumping portion and an outer guiding portion larger in diameter than said pumping portion, pistons fitted in said cylinders, each of said pistons including a pumping portion fitted in the pumping portion of its cylinder and a larger guiding portion fitted in the guiding portion of its cylinder, two trunnions carried by said case upon opposite sides thereof in axial alinement with each other, a reaction member arranged forward of said cylinder barrel and pivoted upon said trunnions, a thrust member carried by said reaction member and cooperating with said pistons to force each piston rearward and cause it to eject liquid from its cylinder during one half of each revolution of said cylinder barrel, a mechanical bearing carried by said reaction member to rotatably support said thrust member and to transmit pumping forces from one to the other, and means for relieving said mechanical bearing from at least a part of said pumping forces including a hydraulic hold-up element carried by said reaction member in engagement with said thrust member and energized by liquid supplied thereto from said cylinders to cause said element to exert hold-up forces upon said thrust member in opposition to said pumping forces and to provide a liquid bearing between said element and said thrust member.

11. In a hydrodynamic machine, the combination of a case, a cylinder barrel rotatably supported within said case and having a plurality of cylinders arranged therein around and parallel to its axis of rotation and a passage leading from each cylinder through the rear end of said cylinder barrel, a valve cooperating with said passages to control the flow of liquid to and from said cylinders, each of said cylinders including an inner pumping portion and an outer guiding portion larger in diameter than said pumping portion, pistons fitted in said cylinders, each of said pistons including a pumping portion fitted in the pumping portion of its cylinder and a larger guiding portion fitted in the guiding portion of its cylinder, two trunnions carried by said case upon opposite sides thereof in axial alinement with each other, a reaction member arranged forward of said cylinder barrel and pivoted upon said trunnions, a thrust member carried by said reaction member and cooperating with said pistons to force each piston rearward and cause it to eject liquid from its cylinder during one half of each revolution of said cylinder barrel, a mechanical bearing carried by said reaction member to rotatably support said thrust member and to transmit pumping forces from one to the other, and means for relieving said mechanical bearing from at least a part of said pumping forces including a hold-up element engaging the front end of said thrust member and having grooves in the rear face thereof, hold-up motors arranged within said element and reacting against said reaction member, and means for supplying liquid from said cylinders to said hold-up motors and said grooves to cause said element to exert hold-up forces upon said thrust member in opposition to said pumping forces and to provide a liquid bearing between said element and said thrust member.

12. In a hydrodynamic machine, the combination of a case, a cylinder barrel rotatably supported within said case and having a plurality

of cylinders arranged therein around and parallel to its axis of rotation and a passage leading from each cylinder through the rear end of said cylinder barrel, a valve cooperating with said passages to control the flow of liquid to and from said cylinders, each of said cylinders including an inner pumping portion and an outer guiding portion larger in diameter than said pumping portion, pistons fitted in said cylinders, each of said pistons including a pumping portion fitted in the pumping portion of its cylinder and a larger guiding portion fitted in the guiding portion of its cylinder, two trunnions carried by said case upon opposite sides thereof in axial alinement with each other, a reaction member arranged forward of said cylinder barrel and pivoted upon said trunnions, a thrust member carried by said reaction member and cooperating with said pistons to force each piston rearward and cause it to eject liquid from its cylinder during one half of each revolution of said cylinder barrel, a mechanical bearing carried by said reaction member to rotatably support said thrust member and to transmit pumping forces from one to the other, and means for relieving said mechanical bearing from at least a part of said pumping forces including a hold-up element engaging the front end of said thrust member and having grooves in the rear face thereof, hold-up motors arranged within said element and reacting against said reaction member, and means for supplying liquid from said cylinders to said hold-up motors and said grooves to cause said element to exert hold-up forces upon said thrust member in opposition to said pumping forces and to provide a liquid bearing between said element and said thrust member.

13. In a hydrodynamic machine, the combination of a case, a cylinder barrel rotatably supported within said case and having a plurality of cylinders arranged therein around and parallel to its axis of rotation and a passage leading from each cylinder through the rear end of said cylinder barrel, a piston fitted in each cylinder and extending forward beyond the end of said cylinder barrel, a valve cooperating with said passages to control the flow of liquid to and from said cylinders, two trunnions carried by said case upon opposite sides thereof in axial alinement with each other, a reaction member arranged forward of said cylinder barrel and pivoted upon said trunnions, a thrust member carried by said reaction member and cooperating with said pistons to force each piston rearward and cause it to eject liquid from its cylinder during one half of each revolution of said cylinder barrel, a mechanical bearing carried by said reaction member to rotatably support said thrust member and to transmit pumping forces from one to the other, and means for relieving said mechanical bearing from at least a part of said pumping forces including hydraulic hold-up means arranged upon opposite sides of the centerline of said machine and engaging the front end of said thrust member, and means for directing liquid from the cylinders from which liquid is ejected to the hold-up means on only the same side of said centerline as those cylinders.

14. In a hydrodynamic machine, the combination of a rotor having a plurality of pistons and cylinders arranged therein parallel to the axis of rotation thereof, a reaction member arranged at one end of said rotor for engaging the outer ends of said pistons and rotatable upon an axis which is normally inclined to the axis of said

rotor to thereby effect reciprocation of said pistons during rotation of said rotor, a substantially flat valve seat arranged upon the other end of said rotor, a cylinder port extending from each cylinder through said valve seat, a floating valve having a substantially flat face to engage said valve seat and ports to cooperate with said cylinder ports to thereby control the flow of liquid to and from said cylinders, and hold-up motors responsive to pressures in said cylinders for urging said valve against said seat, said valve being entirely unsupported by said hold-up motors and being free to tilt a limited distance in any direction relative to the axis of said rotor to thereby enable said hold-up motors to hold the face of said valve uniformly in contact with said valve seat regardless of slight misalignment or deflections of parts of said machine.

15. In a hydrodynamic machine, the combination of a drive shaft and a cylinder barrel rigidly secured to each other to form a substantially unitary rotor having a substantially flat valve seat upon one end thereof, a bearing arranged around said shaft to support said rotor at one end thereof, a second bearing arranged around said valve seat to support said rotor at the other end thereof, pistons and cylinders arranged in said cylinder barrel around said shaft parallel to the axis thereof, a reaction member arranged at the end of said cylinder barrel opposite said valve seat for engaging the outer ends of said pistons and rotatable upon an axis which is normally inclined to the axis of said rotor to thereby effect reciprocation of said pistons during rotation of said rotor, a cylinder port extending from each cylinder through said valve seat, a floating valve having a substantially flat face to engage said valve seat and ports to cooperate with said cylinder ports to thereby control the flow of liquid to and from said cylinders, and hold-up motors responsive to pressures in said cylinders for urging said valve against said seat, said valve being entirely unsupported by said hold-up motors and being free to tilt a limited distance in any direction relative to the axis of said rotor to thereby enable said hold-up motors to hold the face of said valve uniformly in contact with said valve seat regardless of slight misalignment or deflections of parts of said machine.

16. In a hydrodynamic machine, the combination of a rotor having a plurality of pistons and cylinders arranged therein parallel to the axis of rotation thereof, a reaction member arranged at one end of said rotor and having a substantially flat face normally inclined to the axis of said rotor and engaging the outer ends of said pistons to effect reciprocation of said pistons during rotation of said rotor, a support for rotatably supporting said reaction member with its axis of rotation intersecting the axis of said rotor in the plane of said face, means for pivotally supporting said support upon an axis which extends through the point at which the axes of said rotor and said member pass through the plane of said face, means for tilting said support upon said supporting means to thereby vary the inclination of said reaction member relative to the axis of said rotor, a substantially flat valve seat arranged upon the other end of said rotor, a cylinder port extending from each cylinder through said valve seat, a floating valve having a substantially flat face to engage said valve seat and ports to cooperate with said cylinder ports to thereby control the flow of liquid to and from said cylinders, and hold-up motors

responsive to pressures in said cylinders for urging said valve against said seat, said valve being entirely unsupported by said hold-up motors and being free to tilt a limited distance in any direction relative to the axis of said rotor to thereby enable said hold-up motors to hold the face of said valve uniformly in contact with said valve seat regardless of slight misalignment or deflections of parts of said machine.

10 17. In a hydrodynamic machine, the combination of a drive shaft and a cylinder barrel rigidly secured to each other to form a substantially unitary rotor having a substantially flat valve seat upon one end thereof, a bearing arranged around said shaft to support said rotor at one end thereof, a second bearing arranged around said valve seat to support said rotor at the other end thereof, pistons and cylinders arranged in said cylinder barrel around said shaft parallel to the axis thereof, a reaction member arranged at the end of said rotor opposite said valve seat and having a substantially flat face normally inclined to the axis of said rotor and engaging the outer ends of said pistons to effect reciprocation of said pistons during rotation of said rotor, a support for rotatably supporting said reaction member with its axis of rotation intersecting the axis of said rotor in the plane of said face, means for pivotally supporting said support upon an axis which extends through the point at which the axes of said rotor and said member pass through the plane of said face, means for tilting said support upon said supporting means to thereby vary the inclination of said reaction member relative to the axis of said rotor, a cylinder port extending from each cylinder through said valve seat, a floating valve having a substantially flat face to engage said valve seat and ports to cooperate with said cylinder ports to thereby control the flow of liquid to and from said cylinders, and hold-up motors responsive to pressures in said cylinders for urging said valve against said seat, said valve being entirely unsupported by said hold-up motors and being free to tilt a limited distance in any direction relative to the axis of said rotor to thereby enable said hold-up motors to hold the face of said valve uniformly in contact with said valve seat regardless of slight misalignment or deflections of parts of said machine.

15 18. In a hydrodynamic machine, the combination of a rotor having a plurality of pistons and cylinders arranged therein parallel to the axis of rotation thereof, a reaction member arranged at one end of said rotor and having a substantially flat face normally inclined to the axis of said rotor and engaging the outer ends of said pistons to effect reciprocation of said pistons during rotation of said rotor, a support for rotatably supporting said reaction member with its axis of rotation intersecting the axis of said rotor in the plane of said face, means for pivotally supporting said support upon an axis which extends through the point at which the axes of said rotor and said member pass through the plane of said face, means for tilting said support upon said supporting means to thereby vary the inclination of said reaction member relative to the axis of said rotor, a substantially flat valve seat arranged upon the other end of said rotor, a cylinder port extending from each cylinder through said valve seat, a floating valve having a substantially flat face to engage said valve seat and ports to cooperate with said cylinder ports to thereby control the flow of liquid to and from said cylinders, and hold-up motors

with said cylinder ports to thereby control the flow of liquid to and from said cylinders, and hold-up motors responsive to pressures in said cylinders for urging said valve against said seat, said valve being entirely unsupported by said hold-up motors and being free to tilt a limited distance in any direction relative to the axis of said rotor to thereby enable said hold-up motors to hold the face of said valve uniformly in contact with said valve seat regardless of slight misalignment or deflections of parts of said machine.

19. In a hydrodynamic machine, the combination of a drive shaft and a cylinder barrel rigidly secured to each other to form a substantially unitary rotor having a substantially flat valve seat upon one end thereof, a bearing arranged around said shaft to support said rotor at one end thereof, a second bearing arranged around said valve seat to support said rotor at the other end thereof, pistons and cylinders arranged in said cylinder barrel around said shaft parallel to the axis thereof, a reaction member arranged at the end of said rotor opposite said valve seat and having a substantially flat face normally inclined to the axis of said rotor and engaging the outer ends of said pistons to effect reciprocation of said pistons during rotation of said rotor, a support for rotatably supporting said reaction member with its axis of rotation intersecting the axis of said rotor in the plane of said face, means for pivotally supporting said support including trunnions arranged upon opposite sides thereof with the trunnion axes extending through the point at which the axes of said rotor and said member pass through the plane of said face, means for tilting said support upon said trunnions to thereby vary the inclination of said reaction member relative to the axis of said rotor, a cylinder port extending from each cylinder through said valve seat, a floating valve having a substantially flat face to engage said valve seat and ports to cooperate with said cylinder ports to thereby control the flow of liquid to and from said cylinders, and hold-up motors responsive to pressures in said cylinders for urging said valve against said seat, said valve being entirely unsupported by said hold-up motors and being free to tilt a limited distance in any direction relative to the axis of said rotor to thereby enable said hold-up motors to hold the face of said valve uniformly in contact with said valve seat regardless of slight misalignment or deflections of parts of said machine.

20. In a pump, the combination of a rotor having a plurality of cylinders arranged therein parallel to the axis of rotation thereof and a substantially flat valve seat on one end thereof, a floating valve engaging said seat to control the flow of liquid to and from said cylinders, hold-up motors responsive to pressure in said cylinders for urging said valve against said seat, said valve being entirely unsupported by said hold-up motors and being free to tilt a limited distance in any direction relative to the axis of said rotor to thereby enable said hold-up motors to hold the face of said valve uniformly in contact with said valve seat regardless of slight misalignment or deflections of parts of said machine, a substantially flat reaction surface arranged at the other end of said rotor and rotatable upon an axis which is normally inclined to the axis of rotation of said rotor, and a cylindrical piston fitted in each of said cylinders and having an integral outer end or head in engagement with said sur-

face so that each piston is forced into its cylinder by said surface during one half of each revolution of said rotor, the outer end or head of each piston being so shaped that it engages said surface at one side only of the piston axis and causes the pumping force transmitted from said surface to said piston to be resolved into an axial component which moves the piston inward and a radial component which is transmitted through the piston to the wall of its cylinder and so that the axis of the piston remains substantially in alignment with the same point on said surface during rotation of said rotor and said surface at the same speed.

21. In a hydrodynamic machine, the combination of a rotor having a shaft extending from only one end thereof and a substantially flat valve seat on the other end thereof, a bearing arranged around said shaft to support said rotor at one end thereof, a second bearing arranged around said valve seat to support said rotor at the other end thereof, pistons and cylinders arranged in said cylinder barrel around said shaft parallel to the axis thereof, a reaction member arranged at the end of said cylinder barrel opposite said valve seat for engaging the outer ends of said pistons and rotatable upon an axis which is normally inclined to the axis of said rotor to thereby effect reciprocation of said pistons during rotation of said rotor, said rotor having a passage extending from each of said cylinders radially inward and axially outward through said valve seat and constituting a cylinder port, a floating valve having a substantially flat face to engage said valve seat and ports to cooperate with said cylinder ports to thereby control the flow of liquid to and from said cylinders, said cylinder ports and said valve ports being arranged as close as practical to the axis of said rotor to thereby reduce to a minimum the valve area in contact with said valve seat, and hold-up motors responsive to pressures in said cylinders for urging said valve against said seat.

22. In a hydrodynamic machine, the combination of a rotor having a shaft extending from only one end thereof and a substantially flat valve seat on the other end thereof, a bearing arranged around said shaft to support said rotor at one end thereof, a second bearing arranged around said valve seat to support said rotor at the other end thereof, pistons and cylinders arranged in said cylinder barrel around said shaft parallel to the axis thereof, a reaction member arranged at the end of said cylinder barrel opposite said valve seat for engaging the outer ends of said pistons and rotatable upon an axis which is normally inclined to the axis of said rotor to thereby effect reciprocation of said pistons during rotation of said rotor, said rotor having a passage extending from each of said cylinders radially inward and axially outward through said valve seat and constituting a cylinder port, a floating valve having a substantially flat face to engage said valve seat and ports to cooperate with said cylinder ports to thereby control the flow of liquid to and from said cylinders, said cylinder ports and said valve ports being arranged as close as practical to the axis of said rotor to thereby reduce to a minimum the valve area in contact with said valve seat, hold-up motors responsive to pressures in said cylinders for urging said valve against said seat, and means independent of said hold-up motors for restraining said valve

from radial movement while permitting it to have limited axial and tilting movements.

23. In a hydrodynamic machine, the combination of a rotor having a plurality of pistons and cylinders arranged therein around and parallel to the axis of rotation thereof, a reaction member arranged at one end of said rotor to engage the outer ends of said pistons and rotatable upon an axis which normally is inclined to the axis of said rotor to thereby effect reciprocation of said pistons during rotation of said rotor, a substantially flat valve seat arranged upon the other end of said rotor, a bearing arranged upon a portion of said rotor adjacent to said seat to support said rotor at one end thereof, said portion of said rotor being considerably smaller in diameter than the remainder of said rotor to permit said bearing to be relatively small and thereby keep the bearing losses at a minimum, said rotor having a passage extending from each of said cylinders radially inward and then axially outward through said valve seat and constituting a cylinder port, a floating flat valve having a substantially flat face to engage said valve seat and ports to cooperate with said cylinder ports to thereby control the flow of liquid to and from said cylinders, said cylinder ports and valve ports being arranged as close as practical to the axis of said rotor to thereby reduce to a minimum the valve area in contact with said seat, and hold-up motors connected in series with said ports and responsive to the pressures therein for urging said valve against said valve seat.

24. In a hydrodynamic machine having a rotor provided with a plurality of pistons and cylinders which are parallel to the axis of said rotor and are arranged in a circle concentric with said axis, and a thrust member arranged at the front end of said rotor and adapted during rotation of said rotor to force rearward the pistons on one side of the centerline of said machine, the combination of a reaction member arranged forward of said thrust member and restrained from axial movement, a mechanical bearing for rotatably supporting said thrust member and for transmitting pumping forces from one to the other of said members, and

means for relieving said mechanical bearing from at least a part of said pumping forces including a hold-up element engaging the front end of said thrust member and having in the rear face thereof two arcuate pressure ports arranged upon opposite sides of the centerline of said machine and drain grooves arranged between the adjacent ends of said pressure grooves, hold-up motors arranged upon opposite sides of the centerline of said machine and adapted when energized to react against said reaction member and to urge said element against said thrust member, and means for supplying liquid from the cylinders on each side of the centerline of said machine to the hold-up motors and the pressure groove on the same side of said centerline to enable said hold-up element to exert a hold-up force upon said thrust member in opposition to said pumping forces.

25. A combination as set forth in claim 24 in which the radius of said pressure grooves is less than the radius of said piston circle and each of said pressure grooves extends through such an angular distance that the center of said hold-up force is approximately in alignment with the resultant of said pumping forces.

26. A combination as set forth in claim 24 in which the liquid supplied to the hold-up motors and to the pressure groove on each side of said machine is supplied thereto through only one of the motors on each side of said machine.

ADOLF GRAD.
